UNITED STATES PATENT OFFICE.

JOHN A. KNOWLTON, OF DORCHESTER, MASSACHUSETTS, ASSIGNOR TO UNIVERSAL TIDE POWER CO., OF BOSTON, MASSACHUSETTS, AN ORGANIZATION OF MASSACHUSETTS.

HYDRAULIC AIR-MOTOR.

1,342,682.

Specification of Letters Patent.

Patented June 8, 1920.

Application filed August 16, 1919. Serial No. 318,063.

To all whom it may concern:

Be it known that I, JOHN A. KNOWLTON, a citizen of the United States of America, and a resident of Dorchester, in the county 5 of Suffolk and Commonwealth of Massachusetts, have invented certain new and useful Improvements in Hydraulic Air-Motors, of which the following is a specification.

This invention relates to motors and particularly to machines of this description in which the rise and fall of the tide is utilized to compress air and the air thus compressed is adapted to be utilized to drive power generating machinery.

15 The object of the invention is to provide means whereby power may be continuously delivered from a simple and efficient apparatus having means for compressing air and storing it under pressure in a tank or reservoir from which it may be delivered to drive a motor.

20 The invention consists in certain novel features of construction and arrangement of parts which will be fully understood by reference to the description of the drawings and to the claims to be hereinafter given.

25 For the purpose of illustrating the invention, one preferred form thereof is illustrated in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

30 Of the drawings:

40 Figure 1 represents a plan of an apparatus embodying the principles of the present invention.

45 Fig. 2 represents a plan of a portion of the same, showing the power house in section.

Fig. 3 represents a vertical section on line 3.3 on Fig. 2.

Fig. 4 represents a horizontal section on line 4.4 on Fig. 3.

50 Fig. 5 represents a vertical section on line 5.5 on Figs. 2 and 3.

Fig. 6 represents a vertical section on line 6.6 on Fig. 4; and

Fig. 7 represents a diagram of the electric

circuits for operating the gate actuating devices. 55

Similar characters indicate like parts throughout the several figures of the drawings.

In the drawings, 10 is the open water of a 60 bay in which the tide rises and falls and 11 is an inclosed basin communicating therewith.

A dam 12 is built across the narrow passage connecting the open body of water 10 65 and the basin 11, and this dam is provided with two gates 13 and 14 adapted to close passages through said dam.

Within the basin 11, adjacent the dam 12, is built a walled inclosure 15, at one side 70 of which is a sluiceway 16 which communicates at all times with the basin 11 and with the open water 10 when the gate 13 is open.

Within the walled inclosure 15 is a spillway 17 and two reservoirs 18 and 19, which 75 reservoirs are closed at the top as indicated in Figs. 5 and 6 of the drawings.

Between the reservoirs 18 and 19 are two wells 20 and 21, the former of which communicates at the bottom with the reservoir 80 18 by means of the passage 22 while a similar passage 23 connects the bottom of the well 21 with the reservoir 19.

At the upper ends of the wells 20, 21 are floats 24, 25 normally resting upon the supports 26 but adapted to be lifted therefrom by the water in said wells 20, 21, when said water rises above the level of said supports 26. 85

These wells 20, 21 are closed at the top by 90 means of the closures 27 through bearings in which extend the vertical rods 28, 29 secured to the floats 24 and 25 and movable vertically therewith.

Superimposed upon the walled inclosure 95 15, which is preferably built of solid concrete, is a concrete housing 30 in which is located a chamber 31, the top of said housing 30 forming a support or foundation for the hydraulic air motors to be actuated by 100 the tidal water.

Surrounding the chamber 31 and extending beyond each end thereof is a power house 32 which extends upwardly to form a chamber 33 for the air motors 34 and the 105 power generating devices co-acting therewith. These power generating devices form no part of the present invention and conse-

quently are not illustrated in the drawings.

Suitable stairs 35 give access to the chamber 33. Between the reservoirs 18 and 19 are two compartments 36 and 37 separated from each other by a solid wall 38.

The compartment 36 communicates with the basin 11 and the compartment 37 communicates with the spillway 17.

10 The outer ends of these compartments 36, 37 are adapted to be closed by the gates 39 and 40 respectively, said gates being slidably mounted in the passages 41, 42 provided for this purpose in the walled inclosure 15.

The gates 39 and 40 are provided with upward extensions 43, and 44 adapted to contact with suitable gate actuating devices to be hereinafter described.

20 The inner ends of the compartments 36, 37 communicate with the reservoirs 18, 19 by means of passages 45, 46 respectively, these passages being adapted to be closed by the sliding gates 47, 48 movable vertically in 25 the passages 50, 51 provided for this purpose in the walled inclosure 15.

The gates 47, 48 are provided respectively with rack members 52, 53 the teeth of which mesh with spur gears 54 on the revoluble 30 shafts 55 of motors 56 positioned in the chamber 31.

Each revoluble shaft 55 on each side of the motor 56 is provided with a clutch 57 which will permit the gears 54 to be actuated in one direction only, *i. e.* in the direction to lift the rack members 52, 53.

When the rack members 52, 53 are lowered the gears 54 will be rotated thereby without affecting the motors 56.

40 The rack members 52, 53 actuating the gates 47, communicating with the reservoir 18 are secured to the opposite ends of a rocker lever 58 pivoted midway of its length at 59 to a standard 60.

45 It is obvious therefore that by this construction when one of the gates 47 is lifted the companion gate 47 will be lowered.

The rack members 52 operating the gates 48 are similarly connected to the opposite 50 ends of the rocker lever 61 pivoted at 62 to the standard 63 so that when one of the gates 48 is raised the companion gate 48 will be lowered.

The motors 56 are actuated in pairs, the 55 motors 56^a and 56^b being in one electric circuit 64 and the motor 56^c and 56^d being in another electric circuit 65.

The electric circuit 64, is provided with a battery 66 or some similar source of electrical energy. In the circuit 64 is a make-and-break device 67, normally open, and another make-and-break device 68, normally closed.

The make-and-break device 67 is positioned so that when the float 24 reaches the 55 top of the well 20 the member 38 projecting

therefrom will actuate the device 67 to complete the circuit 64 thereby permitting the electric current from the battery 66 to flow through the motors 56^a and 56^b and actuate said motors 56.

70

The operation of the motors 56^a and 56^b will cause the gears 54 to lift the gate 47 controlling the flow of water from reservoir 18 to chamber 36 and at the same time lift the gate 48 controlling the flow of water 75 from the chamber 37 to the reservoir 19.

As before stated when these gates 47, 48 are lifted the companion gates 47, 48 will be lowered.

When the gates 47, 48 being lifted, have 80 reached the limit of their upward movement, the make-and-break device 68 is actuated thereby to open the circuit 64 and prevent the further operation of the motors 56^a and 56^b and consequently any further 85 lifting of said gates. While the gates 47, 48 are in this raised position the water will flow into the reservoir 19 from the basin 11 and be discharged from the reservoir 18 into the spillway 17.

90

The circuit 65 is provided with a battery 69, a make-and-break device 70, normally opened, and a make-and-break device 71, normally closed.

As soon as the water rises, in the reservoir 19, and in the well 21 communicating therewith, sufficiently to raise the float 25 to the top of the well 21, the member 29 on the float 25 will actuate the make-and-break device 70 to close the circuit 65 and actuate the 100 motors 56^c, 56^d, and lift the discharge gate 48 of the reservoir 19 and open the inlet gate 47 of the reservoir 18.

95

As soon as the inlet gate 47 begins to open, the outlet gate 47 will begin to close 105 through the actuation of the rocker lever 58 and as soon as the outlet gate begins to close the movement thereof will close the make-and-break device 68 and leave the circuit 64 in its normal condition ready to be 110 completed by the next upward movement of the float 24.

It is obvious therefore that by means of the mechanism described, the reservoirs 18 and 19 will be successively and alternately 115 filled and emptied of water which is admitted from the basin 11 and delivered to the spillway 17.

Each reservoir 18 and 19 is provided with an air inlet pipe 72 having a non-return 120 valve 73 and each of said reservoirs is likewise provided with an air outlet pipe 74 having a non-return valve 75 therein.

When the water is being lowered in either reservoir 18 or 19 the air will be drawn into 125 said reservoirs, the valve 73 being open and the valve 75 being closed.

As soon as the water admitted to either reservoir begins to rise the valve 73 will be closed and the valve 75 opened by the air 130

pressure in the reservoir but as the outlet pipe is of very small area relatively to the area of the surface of the water rising in the reservoirs 18, 19 it is obvious that the 5 air will be greatly compressed and will be discharged through the pipe 74 under compression.

The air thus rushing through the outlet pipe, 74 is adapted to strike the blades of 10 the turbine, 76 and rotate the shaft thereof and in order to keep the turbines in continuous operation the air rushing into the reservoirs 18, 19 through the pipe, 72 is made to strike the blades of said turbine 76. 15 It is obvious that the turbine 76 will be driven continuously in one direction both when the water is being lowered in the tank 18, 19 or when the water is rising therein.

In practice, the turbines 76 of the motors 20 34 would be connected so as to drive a common driving shaft 77 from which power may be transmitted to actuate a dynamo or other machinery, the connections between the turbines 76 and the driving shaft including 25 a compensating device 78 whereby the said driving shaft 77 will be rotated at a uniform speed even when the turbines 76 are being rotated at different speeds.

As these devices however form no part of 30 the present invention it is believed that it is unnecessary to illustrate the mechanism by which this result is accomplished.

When it is desired to stop the turbines 76, the gates 39, 40 will be closed by means of 35 the gate operating devices 79 which may be of any well known construction having gears to mesh with the teeth of the racks 43, 44.

The spillway 17 must have a capacity 40 sufficient to take care of all the water passing through the reservoirs 18, 19 during the changes of the tide.

It is self evident that the basin 11 must be filled at high tide to the level of the 45 water in the bay 10, the gate 13, being opened for this purpose.

When the basin has been filled, the gate 13 is closed and at this time the gate 14 is also closed and the spillway 17 is empty.

50 The water from the basin 11 may then pass into the reservoirs 18, 19 and be discharged into the spillway 17.

When in the lowering of the tide in the bay 10, the water level is lower than the 55 level of the water in the spillway 17, the gate 14 may be opened and the water lowered.

When the basin 11 has been emptied and the water from the bay 10 is being admitted 60 through the gate 13 it is obvious that if the gate 14 is opened the spillway 17 will be filled more quickly than the basin 11 and when the water in said spillway reaches a higher level than the water in basin 11 the 65 gates 39, 40 may be opened and the water

from the spillway 17 may be admitted to the reservoirs 18, 19 and discharged into the basin 11 and the same results will be obtained as is obtained when the water is passing through the reservoirs in a reverse 70 direction as already described.

Preferably the top of the reservoirs 18, 19 should be below the low water level of the basin 11 and in such a case as the rise and fall of the tide varies in different localities 75 it is obvious that the reservoirs 18 and 19 must be lower relatively to the high water level in basin 11 in localities where there is a great rise and fall of the tide than in other localities where there is but little rise 80 and fall to the tide.

This invention provides a very simple and effective means of utilizing the rise and fall of the tide for creating power to drive 85 dynamos and other machinery.

It is believed that its operation and many advantages will be readily understood without further description.

Having thus described my invention, I 90 claim:

1. In a device of the class described, the combination with an open body of water in which the tide rises and falls, a basin connected by a narrow passage with said open body of water; a dam across said passage; 95 a gate therein; a structure provided with a spillway and a reservoir closed at the top; an air motor; and means for admitting water into said reservoir and therein compressing air adapted to actuate said motor 100 and then discharging said water into said spillway.

2. In a device of the class described, the combination with an open body of water in which the tide rises and falls, a basin 105 connected by a narrow passage with said open body of water; a dam across said passage; a gate therein; a structure provided with a spillway and a reservoir closed at the top; a passage in said dam between 110 said spillway and open body of water; a gate in said passage; an air motor; and means for admitting water into said reservoir and therein compressing air adapted 115 to actuate said motor and then discharging said water into said spillway.

3. In a device of the class described, the combination with an open body of water in which the tide rises and falls, a basin connected by a narrow passage with said open 120 body of water; a dam across said passage; a gate therein; a structure provided with a reservoir closed at the top; an air motor; and means for admitting water into the reservoir and therein compressing air adapted 125 to actuate said motor.

4. In a device of the class described, two reservoirs closed at the top, means for admitting water to said reservoirs alternately and compressing the air therein; motors 130

adapted to be driven by the compressed air in said reservoirs; two wells; a float in each well; and means controlled by the movement of said floats for actuating said water 5 admitting means.

5. In a device of the class described, two reservoirs closed at the top; an inlet gate and an outlet gate to each reservoir, respectively adapted to admit water to and 10 discharge it therefrom; air motors; means for actuating said motors by the compressed air in said reservoirs; and automatic means for controlling the operation of said gates whereby the inlet gate of one reservoir and 15 the outlet gate of the other reservoir are simultaneously opened.

6. In a device of the class described, two reservoirs closed at the top; an inlet gate and an outlet gate to each reservoir, respectively adapted to admit water to and discharge it therefrom; air motors; means for actuating said motors by the compressed air in said reservoirs; a motor for raising one of the gates of each reservoir; and 25 means actuated by the raising of said gate for lowering the other gate of each reservoir.

7. In a device of the class described, two reservoirs closed at the top; an inlet gate 30 and an outlet gate to each reservoir, respectively adapted to admit water to and discharge it therefrom; air motors; means for actuating said motors by the compressed air in said reservoirs, electric motors for 35 raising the gates, said motors being electrically connected in pairs to raise the inlet gate of one reservoir and the outlet gate of the other reservoir; and means controlled by the rise of the water in the first mentioned reservoir for raising the inlet gate of the other reservoir and the outlet gate of the first mentioned reservoir.

8. In a device of the class described, two reservoirs closed at the top; an inlet gate 45 and an outlet gate to each reservoir, respectively adapted to admit water and discharge it therefrom; air motors; means for actuating said motors by the compressed air in said reservoirs; electric motors for raising 50 the gates; said motors being electrically connected in pairs to raise the inlet gate of one reservoir and the outlet gate of the other reservoir; means actuated by the raising of one gate of each reservoir for lowering 55 the other gate of said reservoir; and means controlled by the rise of the water in the first mentioned reservoir for raising the inlet gate of the other reservoir and the outlet gate of the first mentioned reservoir.

60 9. In a device of the class described, two reservoirs closed at the top and adapted to contain water; an inlet gate and an outlet gate to each reservoir; rack members extending upwardly from each gate; an electric motor for each gate; gears coacting 65

with said rack members and actuated by said motor in one direction only; means interposed between the two gates of each reservoir for lowering one gate by the raising of the other gate; and means whereby said 70 motors operate in pairs to raise the inlet gate of one reservoir and the outlet gate of the other reservoir.

10. In a device of the class described, two reservoirs closed at the top and adapted to 75 contain water; an inlet gate and an outlet gate to each reservoir; rack members extending upwardly from each gate; an electric motor for each gate; gears coacting with said rack members and actuated by said 80 motor in one direction only; a rocker member interposed between the two gates of each reservoir and connected to the rack members thereof for lowering one gate by the raising of the other gate; and means whereby 85 said motors operate in pairs to raise simultaneously the inlet gate of one reservoir and the outlet gate of the other reservoir.

11. In a device of the class described, two reservoirs closed at the top and adapted to 90 contain water; an inlet gate and an outlet gate for each reservoir; rack members extending upwardly from each gate; gears coacting with said rack members; an electric motor for each gate and adapted to actuate 95 said gears; clutches between said gears and motors whereby said gears will be rotated by said motors in one direction only; means for simultaneously actuating said motors in pairs to raise the inlet gate of one reservoir and the outlet gate of the other reservoir; and means whereby in the raising of a 100 gate of each reservoir the companion gate of said reservoir will be lowered.

12. In a device of the class described, two 105 reservoirs closed at the top and adapted to contain water; an inlet gate and an outlet gate for each reservoir; a motor for raising each gate; means whereby said gates may be lowered independently of said motors; a 110 float adapted to rise and fall with the water of each reservoir; and means actuated by the float of a reservoir when it reaches a predetermined level for actuating two of said motors to raise the outlet gate of said 115 reservoir and the inlet gate of the other reservoir.

13. In a device of the class described, two reservoirs closed at the top and adapted to 120 contain water; an inlet gate and an outlet gate for each reservoir; a motor for raising each gate; two electric circuits each connecting the motors for raising the inlet gate of one reservoir and the outlet gate of the other reservoir; a make-and-break device 125 in each circuit normally open; means whereby said gates may be lowered independently of said motors; a float adapted to rise and fall with the water of each reservoir; and means on each float adapted to coact with 130

one of said make-and-break devices whereby the outlet gate of the reservoir controlling the rise and fall of a float will be raised and the inlet gate of the other reservoir will be 5 raised simultaneously.

14. In a device of the class described, two reservoirs closed at the top and adapted to contain water; two separated compartments between said reservoirs communicating respectively with a water basin and a spillway and by passages to the bottom of said reservoirs; gates adapted to close said passages; and means for simultaneously raising a gate from one compartment to one 10 reservoir and a gate from the other compartment to the other reservoir.

15. In a device of the class described, two reservoirs closed at the top and adapted to contain water; two separated compartments between said reservoirs communicating respectively with a water basin and a spillway; and by passages to the bottom of said reservoirs; gates adapted to close said passages; and means for simultaneously 20 raising a gate from one compartment to one reservoir and a gate from the other compartment to the other reservoir, and at the same time closing the other two gates.

16. In a device of the class described, two reservoirs closed at the top and adapted to contain water; two separated compartments between said reservoirs communicating respectively with a water basin and a spillway and by passages to the bottom of said reservoirs; gates adapted to close said passages; means for simultaneously raising a gate from one compartment to one reservoir and a gate from the other compartment to the other reservoir; and gates for closing the 30 open ends of said compartments.

17. In a device of the class described; two reservoirs closed at the top and adapted to contain water; two separated compartments between said reservoirs communicating respectively with a water basin and a spillway and by passages to the bottom of said reservoirs; gates adapted to close said passages; means for simultaneously raising a gate from one compartment to one reservoir and 40 a gate from the other compartment to the other reservoir; gates at the open ends of said compartments; and means for raising said gates.

18. In a device of the class described, two reservoirs closed at the top and adapted to contain water; two separated compartments between said reservoirs communicating re-

spectively with a water basin and a spillway and by passages to the bottom of said reservoirs; gates adapted to close said passages; 60 and means for simultaneously raising a gate from one compartment to one reservoir and a gate from the other compartment to the other reservoir; gates at the open ends of said compartments; rack members extending 65 upwardly from said gates; revolute gears coacting with said rack members; and manually operated means for rotating said gears.

19. In a device of the class described, a reservoir closed at the top and adapted to contain water; means for admitting water to said reservoir to compress the air therein; an air motor including in part a revolute member having radial blades; an air outlet pipe leading from the top of said reservoir 70 and adapted to direct a current of air against said blades; and an air inlet pipe leading through the motor casing to the top of said reservoir and adapted to direct a current of air against said blades when air is being 75 drawn into said reservoir.

20. In a device of the class described, a reservoir closed at the top and adapted to contain water; means for admitting water to said reservoir to compress the air therein; 80 an air motor including in part a revolute member having radial blades; an air outlet pipe leading to the casing of said motor and adapted to direct a current of air to strike one side of said blades; and an air inlet pipe 85 to the said casing and from said casing to said reservoir and adapted to direct a current of air against the same side of said blades.

21. In a device of the class described, a reservoir closed at the top and adapted to contain water; means for admitting water to said reservoir to compress the air therein; an air motor including in part a revolute member having radial blades; an air outlet 90 pipe leading to the casing of said motor and adapted to direct a current of air to strike one side of said blades; an air inlet pipe leading to the said casing and from said casing to said reservoir and adapted to direct a current of air against the same side of said blades; and a non-return valve in 95 each of said pipes.

Signed by me at 4 Post Office Sq., Boston, Mass., this 13th day of August, 1919.

JOHN A. KNOWLTON.
